X-RAY DIFFRACTION APPARATUS FOR USE
WITH RADIOACTIVE MATERIALSDavid Harker, Schenectady, N. Y., assignor to
General Electric Company, a corporation of
New York

Application January 13, 1950, Serial No. 138,484

3 Claims. (Cl. 250—51)

1

My invention relates to apparatus for analyzing materials by the use of X-rays and, particularly, to apparatus for analyzing materials which are either radioactive themselves or capable of emitting fluorescent radiations when subjected to X-rays.

In the study of atomic arrangements of materials, the use of diffraction patterns caused by X-rays is well known and has given much information concerning the natures of unknown materials, as well as the structural arrangements of known materials. From a correlation of the wave length of the X-rays employed and the diffraction patterns formed when the material under study is irradiated with such X-rays, valuable information can be obtained with respect to the particle size of the material, the state of strain and other physical conditions and, in the case of unknown specimens, material can be identified. However, when the material being studied is itself radioactive, or is of the type which emits radiations when irradiated by X-rays, it is impossible to obtain accurate diffraction patterns in the usual X-ray spectrometers employed, since the radiations emanating from the material enter the radiation detecting apparatus and, too frequently, completely submerge the diffraction pattern produced by the X-radiation. Accordingly, it is an object of my present invention to provide new and improved X-ray diffraction apparatus which is particularly useful for obtaining diffraction patterns of radioactive materials and materials capable of emitting fluorescent radiations when subjected to X-rays.

In its broadest aspect, my invention employs a curved crystalline substance to rotate the converging diffraction beam from a specimen irradiated with X-rays through an angle such that radioactive radiation from the specimen cannot enter a radiation detector positioned substantially at the focal point of the converging diffraction beam. Additionally, radiation absorbent material is positioned between the material being studied and the radiation detector to eliminate all possibility of radioactive or fluorescent radiations from the material entering the radiation detecting apparatus to produce spurious signals.

The features of my invention which I believe to be novel are set forth with particularity in the appended claims. My invention itself, however, both as to its organization and method of operation, together with further objects and advantages thereof, may best be understood by reference to the following description taken in connection with the accompanying drawing in which Fig. 1 diagrammatically illustrates the diffraction

2

apparatus of my invention, and Fig. 2 illustrates certain characteristics of the apparatus of Fig. 1.

Referring to the drawing, I have shown my diffraction apparatus as comprising a source of X-rays which may be a conventional X-ray tube 1 having an electron emitting filament 2 and a target electrode 3, the electrodes of the X-ray tube 1 having conventional connections to suitable sources of energizing potentials and control apparatus (not shown). The beam of X-rays 4 impinges upon a specimen 5 to be studied. The specimen 5 is supported in any suitable holder 6 arranged to support the specimen 5 at such an angle to the X-ray beam 4 as insures focusing of diffracted X-ray beam 7 at point 8.

The specimen 5 may be of a substance capable of emitting radioactive radiations either per se or through the interaction of the X-rays with the individual atoms of the material. Thus, the specimen 5 may comprise, for example, radium or radium compounds, materials which have been made radioactive by exposure to other radioactive materials, or materials which become a source of X-radiation due to fluorescence when irradiated with X-rays of the beam 4. In the latter category are, for example, compounds of iron or cobalt which are exposed to the X-radiation of a copper target X-ray tube.

The X-ray beam 4, after irradiating the specimen 5, forms a diffracted beam 7 which converges or has its focal point at the narrow entrance slit 8 of a radiation detecting device 9 shown in dotted line. The device 9, which is used in a conventional X-ray spectrophotometer for measuring the intensity of the diffracted rays, may be for example a Geiger counter, an ionization chamber, or a photoelectric multiplier device. Where the specimen 5 is itself radioactive, or is capable of emitting fluorescent radiations when subjected to X-rays, such radioactive radiations also enter the slit 8 along with the desired diffracted beam and produce an undesired background pattern which may be of a greater intensity than that of the desired diffraction pattern and, in many cases, completely submerges the desired pattern.

In order to permit the study of radioactive and similar materials by means of X-ray diffraction apparatus, in accordance with my invention, I place a crystal 10 in the path of the diffracted beam 7 to change the direction of the diffracted beam by an angle 11 of approximately 90°. The crystal 10 may be formed of any crystalline substance of a type which can be bent without breaking up its crystallinity, such as for example mica, quartz, or sapphire, and the exact value of the angle 11 depends on the substance comprising crystal 10. Preferably, crystal 10 is relatively

thin, having a thickness in the order of 0.002 inch or less, and has a fixed curvature. The crystal 10, positioned in the path of the diffracted beam, rotates beam 7 from its normal position to a new position 7', the rotated beam 7' converging substantially at a point 12. Accordingly, at point 12 is located the entrance of a radiation detecting device 9' which may be the same type of device as device 9 and, in my apparatus, replaces device 9. In order to insure that all rays of the diffracted beam 7 are focussed at point 12, crystal 10 has a fixed curvature. The curved crystal 10 must be tangent to an imaginary circle through points 8, 12 and the intersection of ray 7 with crystal 10, and must be curved so that its radius of curvature is equal to the diameter of the imaginary circle just mentioned. Depending on the nature of crystal 10, and the size of the angle 11, one or another of the monochromatic spectral components of the diffracted X-ray beam 7 is bent through angle 11 by crystal 10 to converge at point 12. It is, therefore, possible to arrange matters so that a single wave-length of diffracted radiation only is converged at point 12, while all undesired radiation emanating from specimen 5 (whether diffracted, radioactive or fluorescent) is not recorded by the detector 9'.

In its new position, detector 9' is removed from a direct line of travel of undesired radioactive radiations from the specimen 5. To insure that all undesired radioactive radiations from the specimen 5, including scattered and fluorescent radiations due to the impingement of beam 4 upon the specimen, are prevented from reaching detector 9', a radiation absorbent material, such as for example a lead block 13, is positioned between holder 6 and radiation detecting device 9'.

In Fig. 2, crystal 10 is shown in enlarged view lying upon a circle having its center at a point 14 and being tangent at point 15 to a circle 16 having a diameter lying along the line 14-15 and equal to the distance between these points. In crystal 10, there are lattice planes parallel to the layers of atoms forming the crystal. Such planes are perpendicular to the plane of the drawing in Fig. 2 and are spaced apart a distance d . These planes likewise form an angle α with planes normal to the crystal. According to the well-known Bragg law ($\lambda=2d \sin \theta$), where λ is the wavelength of the impinging rays, the lattice planes reflect incident X-radiation striking the planes at the crystal at an angle θ . The reflected rays, in turn, are converged to a point 12. As a result, rays of the beam 7, which normally would converge at point 8, are reflected by the crystal to converge at point 12. The points 8, 12, 14, 15 all lie on circle 16 which is tangent to the curved crystal at point 15 and which has a radius equal to one-half of the radius of the crystal. Depending upon the nature of the crystal and the wavelength of the incident radiation, the angles α and θ have different values. In the construction of my improved X-ray diffraction apparatus, therefore, the exact position of detector 9' is determined by the nature of the crystal and the center of curvature of the crystal, these factors determining the angle through which beam 7 is rotated by the crystal. Preferably, this angle is relatively large and of the order of 90°, the exact value depending upon the particular crystalline substance employed. Accordingly, entrance 12 to detector 9' is located at the focal point of the rotated beam 7'.

While I have shown a particular embodiment of my invention, it will of course be understood

that I do not wish to be limited thereto since various modifications may be made, and I contemplate by the appended claims to cover any such modifications as fall within the true spirit and scope of my invention.

What I claim as new and desire to secure by Letters Patent of the United States is:

1. Apparatus for studying the diffraction pattern of a material capable of emitting radioactive radiations, either spontaneously or when subjected to X-rays comprising means for producing a beam of X-rays, means for supporting a material to be studied in the path of said beam and inclined at an angle to the axis thereof, a crystal supported in the path of the beam diffracted from the material, said crystal having a fixed curvature and being inclined at an angle to the axis of the beam sufficient to rotate the path of the diffracted beam through a large angle, radiation detecting means positioned to receive the rotated beam, and radiation absorbent material positioned between the material to be studied and said radiation detecting means.

2. Apparatus for studying the diffraction pattern of a radioactive material comprising means for producing a beam of X-rays, a support for radioactive material to be studied positioned in the path of said beam, said support being inclined at an angle to the beam to form a converging beam of diffracted rays, a crystal having a fixed curvature mounted in the path of the diffracted beam, said crystal being inclined at an angle to the path of the diffracted beam to alter the path thereof by substantially 90°, an X-ray detector positioned to receive the altered beam, and X-ray absorbing material positioned between said support and said X-ray detector.

3. Apparatus for studying materials capable of emitting radioactive radiations when subjected to X-rays comprising means for producing a beam of X-rays, means for supporting a material to be studied in the path of said beam, said support being inclined at an angle to the axis of the beam, a crystal having a fixed curvature supported in the path of the beam diffracted from the material, said crystal being inclined at an angle to said diffracted beam sufficient to rotate the path of the diffracted beam by substantially 90°, radiation detecting means positioned to receive the rotated beam, and radiation absorbent material positioned between the material to be studied and said radiation detecting means, said crystal being tangent to a circle passing through said radiation detecting means and the focal point of the diffracted beam, and having its radius of curvature equal to twice the radius of said circle.
